UNITED STATES PATENT OFFICE.

JOSEPH F. MACGREGOR, OF MEADVILLE, PENNSYLVANIA.

COPYHOLDER.

Application filed September 27, 1921. Serial No. 503,658.

To all whom it may concern:

Be it known that I, JOSEPH F. MACGREGOR, a citizen of the United States, residing at Meadville, in the county of Crawford and State of Pennsylvania, have invented new and useful Improvements in Copyholders, of which the following is a specification.

This invention relates to improvements in copy holders especially designed for attachment to typewriting machines, an object of the invention being to provide means whereby a copy may be supported in the most advantageous manner.

Another object of the invention is the provision of a copy holder in which the copy support is adjustable to fit note books or sheets of different sizes, so that the copy may be held in position to prevent buckling or folding and the entire face of the copy exposed.

A further object is the provision of means associated with the copy holder, whereby the leaves may be folded over the top and held against the back of said holder, so as to be out of the way of the succeeding pages or leaves.

With the above and other objects in view, the invention further includes the following novel features and details of construction, to be hereinafter more fully described, illustrated in the accompanying drawings and pointed out in the appended claims.

In the drawings:—

Figure 1 is an elevation of a copy holder embodying the invention.

Figure 2 is a sectional view on the line 2—2 of Figure 1.

Figure 3 is a similar view on the line 3—3 of Figure 1.

Figure 4 is a like view on the line 4—4 of Figure 1.

Figure 5 is an enlarged section on the line 5—5 of Figure 1.

Figure 6 is a detail perspective view of the securing clamp.

Referring to the drawings in detail, wherein like characters of reference denote corresponding parts, the reference character 10 indicates the holder proper against which the copy is adapted to rest. This holder is of sectional formation and includes an upper section 11 and a lower section 12, the former including a transversely disposed plate 13 which is provided along one edge with a longitudinally disposed

channel 14 for the reception of an L-shaped arm 15, to which the plate 13 is secured. Extending downwardly from the plate 13 are spaced arms or fingers 16 and these 60 fingers together with the plate 13 provide a back for the upper end of a note book or copy sheet.

In order to secure a note book or copy sheet to the section 11, the latter is provided with a spring clamp 17, whose opposite ends are formed into loops 18 which pass through openings provided in the plate 13 and surround the edge of the plate which receives one end of the L-shaped arm 15. 65 The upper end of the copy may thus be securely clamped to the section 11 and the leaves may be folded over upon the back of the holder and held in such folded position through the medium of a spring arm 18' 70 which is secured to and extends inwardly from the L-shaped arm 15.

The section 12 of the holder includes a substantially Z-shaped plate 19 which is arranged to provide a lower horizontal supporting ledge 20 and an upper guide flange 21. The flange 21 is provided with spaced openings which slidingly receive and guide the fingers 16 of the section 11 which extend downwardly toward this section 12 so as to bridge the space between the two sections. The plate 12 is provided with a spring finger 22 which is adapted to engage and hold the lower end of the copy. 85

The sections 11 and 12 of the holder are 90 relatively adjustable and for this purpose, the section 12 is carried by a slide 23 which is provided with an opening 24 for the passage of one end of the L-shaped arm 15, so that the said slide may be adjusted upon 95 this arm to regulate the size of the holder and held in adjusted position through the medium of a set screw 25.

Pivots secured to the slide 23 is one 100 end of an L-shaped supporting arm 26, the latter being of sectional formation and including a section 27 and a section 28, the first mentioned section being secured to the slide 23 and pivotally adjusted with respect thereto by means of a set screw 29. The 105 angular position of the holder may thus be regulated to suit the operator. The opposite end of the section 27 of the arm 26 is longitudinally and rotatably adjustable within one end of a sleeve 30, the latter serving as a connection between the section 27 and the section 28, the last mentioned section 110

being permanently secured in one end of the sleeve. The opposite end of the section 28 is provided with a right angular extension 31 which is removably and pivotally received within a socket 32 provided in a clamp 33. This clamp is of U-shaped formation and is adapted to engage over a convenient part of a typewriting machine and to be held against accidental displacement 10 through the medium of a set screw 34. The construction of the clamp 33 may be varied to suit the particular make of machine to which the holder is attached.

It will be seen from the foregoing description and the accompanying drawings, that the invention provides a copy holder which may be adjusted to the size of the copy in use, being further adjustable to regulate the horizontal and vertical angular position of the holder, while the height 20 of the holder with respect to the machine may also be regulated. By means of the connection between the arm 26 and the clamp 33, the holder may be positioned toward either the front or rear of the machine, at 25 the option of the user.

The invention is susceptible of various changes in its form, proportions and minor details of construction and the right is here- 30 in reserved to make such changes as properly fall within the scope of the appended claims.

Having described the invention what is claimed is:—

1. A copy holder comprising a sectional support, one of said sections including an upper horizontally disposed member, spaced fingers extending therefrom and the other section including a lower horizontally disposed substantially Z-shaped member having a horizontally disposed upper flange extending longitudinally thereof and provided with spaced openings therein to slidably receive the spaced fingers, and a long arm carried by the upper member, a guide block 45 carried by the lower member and having an opening therethrough to slidably receive the arm, means for holding the block and arm against relative movement and supporting means for the holder. 50

2. A copy holder comprising a sectional support including an upper section and a lower section, said upper section comprising a horizontally disposed plate and spaced vertically disposed rods having their upper ends secured to the plate, one of said rods being relatively long, said lower section comprising a horizontally disposed substantially Z-shaped plate including an upper flange provided with spaced openings to 60 slidably receive the lower ends of the spaced rods and a lower copy supporting flange, an attaching arm and means carried by the attaching arm for sliding and adjustable engagement with the relatively long rod. 65

In testimony whereof, I affix my signature.

JOSEPH F. MacGREGOR.
